AIR MIXING SMOKING PIPE AND THE LIKE

Charles Goetz, New York, N. Y.

Application February 1, 1940, Serial No. 316,773

3 Claims. (Cl. 131—216)

This invention relates to new and useful improvements in a double trap air mixing smoking pipe and the like.

More specifically, the invention proposes the construction of a smoking pipe characterized by the provision of a double trap located within the stem thereof for collecting juices and particles of tobacco from the smoke entering the stem in a manner to permit only cool smoke to enter one's mouth.

Still further it is proposed to characterize the pipe by a tobacco bowl continuing at its bottom into a rearwardly extending stem portion having the first trap located therein for collecting juices as the smoke passes from the bowl.

Still further it is proposed to mount a mid stem section upon the rearwardly extending stem portion of the bowl, provided with a second trap compartment in a manner to collect any juices not collected by the first mentioned trap.

Still further it is proposed to provide a mouth bit stem section mounted upon the free end of the mid stem section and provided with a smoke passage for conveying the cleaned smoke from the second trap section into one's mouth.

Still further it is proposed to provide a passage between the trap sections through which the smoke is adapted to pass, and an auxiliary passage adapted to be utilized for conveying the smoke in the event that said first passage becomes clogged with juices or bits of tobacco.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a longitudinal sectional view of a smoking pipe constructed in accordance with this invention.

Fig. 2 is a vertical sectional view on the line 2—2 of Fig. 1.

Fig. 3 is a vertical sectional view on the line 3—3 of Fig. 1.

Fig. 4 is an elevational view of the aluminum, protector per se.

Fig. 5 is a plan view of the mouth bit stem section per se.

Fig. 6 is an enlarged detailed view of a portion of Fig. 1 but illustrating a modification of the invention.

Fig. 7 is a view looking in the direction of the line 7—7 of Fig. 6.

Fig. 8 is a vertical sectional view on the line 8—8 of Fig. 6.

The double trap air mixing smoking pipe, according to this invention, includes a tobacco bowl 10 having a rearwardly extending stem por-

tion 10^a. This rearwardly extending stem portion is formed with an inwardly extending opening 11 forming the first juice trap compartment. The interior of the bowl is hollowed out, as indicated at 10^b, and is adapted to receive the tobacco to be smoked. A passageway 12 connects the interior 10^b of the bowl 10 with the inwardly extending opening 11 for permitting the smoke to pass from the hollow to the opening.

10 The bottom of the hollow 10^b is protected by means of an aluminum member 13 set into the bottom thereof and which has a reduced end 13^a threadedly engaged into the passageway 12. This aluminum protector 13 is provided for the purpose of preventing the tobacco from coming in direct contact with the heel of the bowl to prevent the tobacco located within this area from becoming soggy while the pipe is being smoked.

A mid stem section 14 having a front end 20 shoulder portion 14^a is connected with the rearwardly extending stem portion 10^a. This mid stem section 14 has its shoulder front end portion 14^a extended into the rear portion of the stem portion 10^a. This mid pipe section 14 is 25 further hollowed, as indicated at 14^b, for forming the second juice trap compartment. This hollow 14^b extends inwards from the rear end of the mid stem section 14.

30 A mouth bit section 15 is connected with the mid stem section 14. More specifically, this mouth bit section 15 is provided with a front end shoulder portion 15^a which is inserted into the rear portion of the hollow 14^b of the mid stem pipe section. This mouth bit stem 15 is further 35 provided with a smoke passage 16 for conveying the smoke from the second juice trap compartment to the interior of one's mouth. The front end shoulder portion 14^a of the mid stem section 14 is provided with a coaxially extended opening 14^c through which a tube 17 extends. This tube 17 has one of its ends partially extended into the first trap compartment 14^b and is provided for the purpose of conveying the smoke from the first trap compartment to the second trap compartment.

The front end of the smoke passage 16 is 40 enlarged, as indicated at 16^a, and carries a second tube 18. This tube 18 has its rear end extended into the enlarged opening 16^a and its front end 45 extended partially into the second juice trap compartment 14^b. This tube 18 is provided for connecting the interior of the second juice trap 14^b with the smoke passage 16.

50 The mouth bit stem section 15 is further provided with an air vent aperture 19 extending from the top wall of the smoke passage to the exterior of the bit stem section 15. This aperture 19 is provided for permitting a quantity 55 of fresh air to enter the smoke passage and mix

with the smoke passing therethrough in a manner to cool the same before it enters the mouth.

The operation of this invention is as follows:

The pipe is assembled as shown in Fig. 1 and the tobacco to be smoked is placed within the hollow 10^b of the pipe bowl 10. The tobacco is then lit and when one draws upon the mouth bit stem section the smoke will pass from the burning tobacco to the first juice trap compartment 11. Within this compartment all juices and particles of tobacco will be separated from the smoke before the same enters the tube 17. Further drawing upon the pipe stem section will cause the smoke to pass through the stem 17 into the second juice compartment 14^b. This juice compartment acts to separate any juices or bits of tobacco from the smoke which was not separated by the first juice trap compartment to clear the smoke of all juices before entering the tube 18. From the tube 18 the smoke will enter the smoke passage 16 where it will be mixed with a quantity of air entering the aperture 19 to cool the smoke before the same enters the mouth.

From an inspection of Fig. 1 it will be noted that the pipe stem section 15 may be separated from the mid stem section 14 and that the mid stem section may be separated from the rearwardly extending stem portion 10^a to permit each of the juice trap compartments to be conveniently and thoroughly cleaned of any juices collected therein.

According to the modification of the invention shown in Figs. 6-8 inclusive, the construction of the pipe is similar to that previously described, except for the provision of an auxiliary passage 20 between the first juice trap compartment 11 and the second juice trap compartment 14^b and which is adapted to be used in the event the tube 17 becomes clogged with bits of tobacco or tobacco juice. This passage 20 has a portion 20^a formed in the rearwardly extending stem portion 10^a, and still another portion 20^b formed in the front end of the mid stem section 14. These portions are adapted to be aligned with each other as shown in Figs. 6 and 7 for permitting the smoke to freely pass therethrough. However, when the tube 17 is clear it is more desirable to have the portions 20^a and 20^b out of alignment so as to cause the smoke to pass only through the tube. The aligned position of these portions of the passage 20 is controlled by means of markings 21 and 22 formed on the adjacent ends of the rearwardly extending stem portion 10^a and the mid stem section 14. When these markings 21 and 22 are aligned, as shown in Fig. 7, the portions 20^a and 20^b of the passage 20 will also be in alignment. The reverse also holds true, that is, when the markings 21 and 22 are out of alignment, the portions 20^a and 20^b will also be out of alignment.

In other respects this form of the invention is similar to the previous form and like parts are identified by like reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new, and desire to secure by United States Letters Patent is:

1. In a smoke pipe, a stem portion having a cylindrical bore extended inwards from its rear end forming a tobacco juice first trap compartment, a mid-stem section having a front end shouldered portion of a diameter equal to the diameter of said bore and extended into the front of said bore, said mid-stem section being formed with a bore extended inwards from its rear end forming a tobacco juice second trap compartment, said front end shouldered portion being formed with a coaxial passage for conveying smoke from said first trap compartment to said second trap compartment, and a normally closed passage extending between said compartments above said passage and substantially parallel thereto and being adapted to be used for conveying smoke when said first-mentioned opening becomes clogged.

2. In a smoke pipe, a stem portion having a cylindrical bore extended inwards from its rear end forming a tobacco juice first trap compartment, a mid-stem section having a front end shouldered portion of a diameter equal to the diameter of said bore and extended into the front of said bore, said mid-stem section being formed with a bore extended inwards from its rear end forming a tobacco juice second trap compartment, said front end shouldered portion being formed with a coaxial passage for conveying smoke from said first trap compartment to said second trap compartment, and a normally closed passage extending between said compartments above said passage and substantially parallel thereto and being adapted to be used for conveying smoke when said first-mentioned opening becomes clogged, said latter mentioned passage being formed partially within said stem portion and partially within said mid-stem section and the parts thereof being normally disaligned to prevent the passage of smoke therethrough.

3. In a smoke pipe, a stem portion having a cylindrical bore extended inwards from its rear end forming a tobacco juice first trap compartment, a mid-stem section having a front end shouldered portion of a diameter equal to the diameter of said bore and extended into the front of said bore, said mid-stem section being formed with a bore extended inwards from its rear end forming a tobacco juice second trap compartment, said front end shouldered portion being formed with a coaxial passage for conveying smoke from said first trap compartment to said second trap compartment, and a normally closed passage extending between said compartments above said passage and substantially parallel thereto and being adapted to be used for conveying smoke when said first-mentioned opening becomes clogged, said latter mentioned passage being formed partially within said stem portion and partially within said mid-stem section and the parts thereof being normally disaligned to prevent the passage of smoke therethrough, said mid-stem section being turnably connected with said stem portion, whereby said mid-stem section may be turned relative to said stem portion to align the parts of said second passage so that smoke may pass therethrough in the event said first passage should become blocked with bits of tobacco.

CHARLES GOETZ.
